UNITED STATES PATENT OFFICE.

PHILIP T. DODGE, OF NEW YORK, N. Y., ASSIGNOR TO MERGENTHALER LINOTYPE COMPANY, A CORPORATION OF NEW YORK.

TYPOGRAPHICAL MACHINE.

1,074,848.

Specification of Letters Patent.

Patented Oct. 7, 1913.

Application filed December 18, 1912. Serial No. 722,886.

To all whom it may concern:

Be it known that I, PHILIP T. Dodge, a citizen of the United States, and residing at New York, in the county of New York and State of New York, have invented certain new and useful Improvements in Typographical Machines, of which the following is a specification, reference being had therein to the accompanying drawing.

10 My invention relates to typographical machines, wherein are provided coöperating members to form type or bars with printing characters thereon. For instance, the well-known linotype machines are 15 equipped with a slotted mold and with jaws to hold the composed line of matrices in proper relation thereto, and also with means to supply molten metal to the mold, so as to cast a slug or linotype therein and 20 against the matrices which produce the type characters thereon. Further, molds of this description are frequently made adjustable so as to vary the length of the slot therein, and thus to produce slugs of different 25 length, as may be required. This adjustment is secured by substituting a different mold liner between the cap and body portion, or by the employment of a liner which is movable relatively thereto, at will. 30 It is one of the principal objects of my invention to provide a mold with this capability for longitudinal adjustment, and also having a matrix confining jaw movably connected thereto, in such manner that 35 an alteration in length simultaneously moves the jaw to its corresponding position, thus not only obviating the necessity for separate adjustment, but also insuring the proper location of the jaw with relation to 40 the presented line. This and other features of my invention will be subsequently described more in detail.

In the drawing, I have shown my invention in preferred form and by way of 45 example, and in connection with the form of mold already mentioned, but obviously many variations and alterations may be made therein, and in its mode of application, and still be comprised within its spirit. 50 Generally speaking, I desire it to be understood that I do not limit myself to any specific form or embodiment, except in so far such limitations are specified in the claims.

55 Referring to the drawing: Figure 1 is a

perspective view of the mold, etc., having my invention applied thereto; Fig. 2 is a detached view of the liner and jaw; and Fig. 3 is a transverse vertical section, taken substantially on the line 3-3 in Fig. 1.

Referring to the drawing, the mold comprises the customary body portion A, cap B, and intermediate movable liner C, arranged so that the length of the mold may be regulated at will. The liner C is longitudinally slotted, as at D, and is mounted between the body portion and cap, the several elements of the mold being clamped together by the screw E, which passes through the slot and holds the liner in any set position with relation to the other parts.

The composed line comprises the matrices X and spacers Y, and is held in casting relation to the mold between the jaws F and G. In order to permit the proper positioning of the jaw F, I connect it to, or form it integral with the liner C, so that when the latter is adjusted to alter the length of the mold, the jaw F will be simultaneously moved thereby into its corresponding and correct position.

In order to give rigidity to the jaw F, and to prevent it from imparting twisting or other strains to the liner C and cap B, I preferably arrange for a sliding engagement between it and the body portion A, this sliding connection being shown in the drawing in the form of a dovetail guide H.

From the foregoing description, it will be noted that the jaw F is supported directly by the mold and will be carried with it in its movement, so that the jaw and liner may be permanently adjusted with relation to the mold for any given length of lines without requiring any further alterations in the machine parts.

As previously stated, I have shown my invention simply in preferred form and by way of example, and obviously many changes and variations therein will suggest themselves to those skilled in the art without departure from its scope.

Having thus described my invention, its construction and mode of operation, what I claim and desire to secure by Letters Patent of the United States is, as follows:

1. In a typographical machine, the combination with a slotted mold comprising a cap, a body portion and an intermediate liner adjustable to vary the length of the

mold slot, a matrix confining jaw movably carried by the mold and connected to said liner, whereby the corresponding adjustment of said parts will be insured.

5. 2. In a typographical machine, the combination of a mold comprising an adjustable part and a relatively fixed part, and an adjustable matrix confining jaw connected to said movable part and engaging and supported by said fixed part.
10. 3. In a typographical machine, the combination of a mold comprising a cap and

body portion and an intermediate liner adjustable to vary the length of the mold slot, and an adjustable matrix confining jaw connected to said liner and mounted to slide in guides upon the body portion. 15

In testimony whereof I affix my signature in presence of two witnesses.

PHILIP T. DODGE.
